PREFABRICATED BUILDING

Dave Chapman, Chicago, Ill., assignor to Panelfab Products, Inc., North Miami, Fla., a corporation of Florida

Filed July 2, 1963, Ser. No. 75,625

Term of patent 14 years

(Cl. D13—1)

FIG. 1 is a perspective view looking down toward the left front corner of the prefabricated building.

FIG. 2 is an elevational view looking toward the right at FIG. 1.

FIG. 3 is an elevational view of the rear of the building.

FIG. 4 is an elevational view looking toward the left at FIG. 3.

FIG. 5 is a front elevational view of the building; and

FIG. 6 is a sectional floor plan view taken substantially along the line 6—6 of FIG. 5.

The dominant features of my design reside in the portions shown in full lines in the drawings.

I claim:

The ornamental design for a prefabricated building, substantially as shown and described.
